The ornamental design for a staple cartridge for a linear surgical stapler as shown and described.

DESCRIPTION

FIG. 1 is a perspective view of a staple cartridge for a linear surgical stapler, showing our new design;
FIG. 2 is a front elevational view of the staple cartridge of FIG. 1;

FIG. 3 is a rear elevational view of the staple cartridge of FIG. 1;

FIG. 4 is a left side elevational view of the staple cartridge of FIG. 1;

FIG. 5 is a right side elevational view of the staple cartridge of FIG. 1;

FIG. 6 is a top plan view of the staple cartridge of FIG. 1;
FIG. 7 is a bottom plan view of the staple cartridge of FIG. 1;

FIG. 8 is a perspective view of another staple cartridge for a linear surgical stapler, showing our new design;
FIG. 9 is a front elevational view of the staple cartridge of FIG. 8;

FIG. 10 is a rear elevational view of the staple cartridge of FIG. 8;

FIG. 11 is a left side elevational view of the staple cartridge of FIG. 8;

FIG. 12 is a right side elevational view of the staple cartridge of FIG. 8;

FIG. 13 is a top plan view of the staple cartridge of FIG. 8;
FIG. 14 is a bottom plan view of the staple cartridge of FIG. 8;

FIG. 15 is a perspective view of another staple cartridge for a linear surgical stapler, showing our new design;
FIG. 16 is a front elevational view of the staple cartridge of FIG. 15;

FIG. 17 is a rear elevational view of the staple cartridge of FIG. 15;

FIG. 18 is a left side elevational view of the staple cartridge of FIG. 15;

(Continued)

FIG. 19 is a right side elevational view of the staple cartridge of FIG. 15;
 FIG. 20 is a top plan view of the staple cartridge of FIG. 15;
 and,
 FIG. 21 is a bottom plan view of the staple cartridge of FIG. 15.

The broken lines in the drawings are included for the purpose of illustrating portions of the staple cartridge for a linear surgical stapler that form no part of the claimed design.
